CHARLES H. MEIGS, OF PHILADELPHIA, PENNSYLVANIA, ASSIGNOR TO MACANDREWS & FORBES COMPANY, OF CAMDEN, NEW JERSEY, A CORPORATION OF NEW JERSEY.

FIRE-EXTINGUISHING APPARATUS.

1,312,559.

Specification of Letters Patent. Patented Aug. 12, 1919.

Application filed February 28, 1918. Serial No. 219,600.

To all whom it may concern:

Be it known that I, CHARLES H. MEIGS, a citizen of the United States, residing at Philadelphia, in the county of Philadelphia 5 and State of Pennsylvania, have invented new and useful Improvements in Fire-Extinguishing Apparatus, of which the following is a specification.

This invention relates to improvements in 10 fire-extinguishing apparatus and more particularly to apparatus for this purpose wherein the chemical components of the charge are brought together by inverting the container.

15 The charge components of this type of apparatus are generally of acid and soda content, the acid component being carried by a receptacle mounted within the container, this receptacle being generally closed by a 20 suitable stopple which is moved from its seat when the apparatus is inverted. While the present invention is adapted for use in connection with different forms which this class 25 of invention may take on, it is especially adapted for use in connection with apparatus operating under foam-extinguishing principles, in which the acid component is generally in the form of a solution and therefore requires a receptacle of considerable 30 capacity to contain the proper amount of solution proportioned to the soda solution component, the latter preferably carrying the foam-producing ingredient.

Owing to the capacity requirement, the 35 acid receptacles are generally formed of metal, the receptacle having an open top and having a suitable seat for the stopple, the latter generally being formed of lead or a suitable alloy, the parts being arranged to 40 withstand corrosive or other action by the acid. In this latter type of apparatus, the stopple is generally mounted in a cage of suitable type, the stopple normally resting on its seat and being adapted to fall or 45 gravitate from its seat when the container is inverted, thus permitting the acid content to be brought into contact with the soda solution and generate the extinguishing medium. Both components are in solution 50 form and should be brought together in the proper proportions to secure the desired result.

While the weight of the stopple is assumed to be sufficient to provide unseating

of the stopple under this inverting action, 55 this theoretical result is not generally obtained in practice—excepting under extremely favorable conditions—it being found that the stopple is either held to its seat throughout the area of the contacting 60 faces or at some portion or portions thereof; in the former case the receptacle does not open when the apparatus is inverted, and in the latter case the movement of the stopple is so disarranged as to materially affect the 65 general operation through improper discharge of the acid solution and thereby varying the desired proportions between the solutions being commixed.

This result is especially liable where the 70 apparatus has remained inactive for a considerable length of time, and is due to the fact that there is a tendency of the acid content to crystallize under certain conditions. For instance, if the receptacle is moved 75 about so as to shake or splash its contents, the acid content of the film remaining on the sides of the receptacle, when the solution comes to rest, may become crystallized and form a deposit on the walls. And where 80 this splashing action is sufficient to carry the contents to the top of the receptacle, the solution may extend on to the seat or the seating face of the stopple, a condition which permits this crystallization action to 85 take place at the seating point of the stopple. As the magnitude of movement ordinarily sufficient to cause a splashing action of this extent will generally shift the stopple from 90 its seat, it will be understood that the film may readily extend between the stopple and its seat. In this latter condition, when crystallization takes place, the deposits form a means for retaining the stopple seated, and when the apparatus is inverted, this crystallization must be broken down before the desired gravity action of the stopple can be 95 properly had, the crystallization tending to form a binder which more or less firmly holds the stopple to its seat.

In a companion application—Ser. No. 211,308—I have pointed out ways in which this problem may be met. In the present invention I have provided another and a different treatment of this problem, the break 105 down of the completed crystallization being provided by the automatic application of a blow to the stopple when the apparatus is

inverted, this blow—in the nature of a hammer blow—being given in the direction of opening movement of the stopple. Several ways are herein illustrated by means of 5 which this result can be obtained, each form employed being carried by the stopple itself and thus remaining as a permanent part of the apparatus ready for use each time the apparatus is charged, the operation providing 10 no damage to parts. In each case the blow-imparting element is normally located within the receptacle and, when the apparatus is in inactive position, aids in retaining the stopple seated, thus reducing the liability 15 of stopple movement from its seat under a shaking action and tending to prevent the solution from passing between the stopple and its seat with the result that the extent of crystallization action is more or less limited. Since the blow is provided on 20 the stopple itself with no material damage thereto, no damage to other parts is had.

In addition, the arrangement is simple and comparatively inexpensive and can be 25 applied to existing structures with substantially no change excepting as to the stopple itself, a change readily provided by the substitution of one form of stopple for another.

To these and other ends, therefore, the 30 nature of which will be readily understood as the invention is hereinafter disclosed, said invention consists in the improved construction and combination of parts hereinafter fully described, illustrated in the accompanying drawings, and more particularly 35 pointed out in the appended claims.

In the accompanying drawings, in which similar reference characters indicate similar parts in each of the views:

40 Figure 1 is a vertical sectional view of an apparatus of the class referred to showing one embodiment of the present invention applied thereto.

Fig. 2 is an enlarged sectional view of 45 parts shown in Fig. 1.

Fig. 3 is a similar view showing a different embodiment of the invention.

As heretofore pointed out, the principles 50 of the present invention are applicable for use in connection with apparatus of this type generally and especially where the stopple is formed of metal. The disclosure made herein, shows the application of these principles to apparatus of the foam-extinguishing type, a type where the difficulty to be remedied is especially prominent for reasons heretofore pointed out. It is to be understood, however, that the invention is not limited in its application to the specific type 55 of apparatus disclosed.

In the drawings I have shown it as applied to the type of apparatus disclosed in the companion application above identified, 10 indicating the container having a bottom 65 11, a neck 12, a cap 13 threaded thereto,

and a flexible discharge structure 14. 15 indicates the inner receptacle which extends practically to the bottom of the container and has its upper end provided with a stopple 16, the latter being normally mounted 70 on a seat at the top of receptacle 15 and located within a cage 17 which extends into neck 12, the cage being adapted to act more or less as a guide for the stopple and at the same time permit free gravity movements 75 of the latter when the apparatus is inverted. In this particular embodiment, the seat is practically in the form of an edge which enters into an annular groove on the lower face of the stopple, the bottom of the groove 80 forming the stopple seating face, the arrangement being such as to provide for a minimum area of contact between the stopple seating face and the edge of the seat. However, this arrangement is specific to the 85 form of apparatus referred to in the companion application, and is not intended to limit the present invention as to use.

Referring more particularly to the present invention, two forms of which are disclosed, the purpose is to provide a blow to the stopple when the apparatus is inverted, this blow being designed more particularly for the purpose of disrupting any binding effect between the stopple and its seat which 95 may have been provided by a crystallization action. Owing to the character of the acid contents of the receptacle, this stopple is generally of lead or suitable alloy in order that corrosive action under the acid may be 100 reduced to a minimum. Hence, the blow-imparting structure should be of such character as to provide the necessary power to produce the action but without tending to produce any material damage to the stopple 105 itself, it being understood, of course, that the apparatus is designed to be recharged after having been used, so that the stopple should remain as a permanent part of the apparatus, although removable at will. 110

Referring more particularly to Figs. 1 and 2, this blow-imparting structure is provided by a weighted element such, for instance, as a ball 20, this ball being located within a cup-shaped receptacle 21 which is 115 removably secured to the under face of the stopple, receptacle 21 having a length such as will permit the ball to travel a distance sufficient to obtain the desired impetus so that in contacting with the stopple the blow 120 will be more or less in the nature of a hammer blow. A simple form of apparatus is provided by forming the stopple with a boss 16 carrying peripheral threads, the threaded boss being produced at the time 125 of the casting of the stopple, thus providing for a coarse thread to the boss. The upper end of receptacle 21 is formed with a complementary configuration which will readily thread on to the boss, the result be- 130

ing that a runway is provided beneath the stopple of a desired length, this runway being practically closed to the acid solution through the threaded connection, so that the ball is permitted to move with freedom throughout the length of receptacle 21. Since receptacle 21 depends from the stopple when the latter is closed, ball 20 will normally lie at the bottom of this receptacle, the result being that the stopple is not only held to its seat by its own weight, but also by the presence of this ball weight located below the plane of the seating face, thus providing an efficient stopple-retaining effect during such movements of the apparatus as are not designed to provide for the inverting operation. Obviously, this retaining action will reduce the area of crystallizing binding, since the possibility of the solution passing between the seat and seating face is materially reduced.

When, however, the apparatus is inverted, the ball freely moves to the opposite end of the runway and into contact with boss 16^a, imparting a blow—on the order of a hammer blow to the boss and obviously to the stopple, the blow being sufficient to break down any binding effect which the crystallization action may have produced. As will be understood, the desired effect is produced not simply because of the weight of the ball, but by reason of the impetus of the latter and the more or less hammer-like character of the blow. Consequently the weight of the ball may be comparatively small, a desirable feature in order that its size may be maintained comparatively small and permitting receptacle 21 to be of a correspondingly small cross section, it being understood, of course, that receptacle 21 should not materially obstruct the discharge of the solution after the stopple has moved from its seat. Furthermore, since the ball is traveling in a runway which is entirely or substantially free from solution, it will be understood that the length of receptacle 21 need not be excessive, thus reducing the amount of obstruction to the outflow of the acid solution, and at the same time providing against movement of the ball in such manner as to produce any material battering of the stopple.

While I have referred to member 20 as a ball, it will be understood that this element may have various configurations, the essential feature being that it is able to pass freely from one end of the runway to the other in order that it may impart the blow to the stopple.

Obviously, receptacle 21 will be treated to withstand corrosive action of the acid, it being understood that when the apparatus is inverted, this receptacle is in the direct path of travel of the acid content.

In Fig. 3 I have shown a different em-

bodiment of the principles of the invention, the blow-imparting element not being enclosed, the weight—shown as of ball form—being attached to the stopple by a flexible chain 22 of suitable length, one end of the chain being secured to the under face of the stopple—the latter preferably having a boss to receive the blow, although this is not essential—the opposite end of the chain being connected to the ball. The chain and ball will, of course, be treated to withstand the corrosive action of the acid solution. The length of the chain will, of course, be such as will permit a length of movement to the ball sufficient to obtain the desired impetus of the latter, and may be of greater length than the length of receptacle 21, since the movement of the ball is more or less through the solution, but this does not materially restrict the free outflow of the solution from receptacle 15, since both chain and ball move onto the stopple when the apparatus is inverted and are thus carried to a point where the outflow of solution is not restricted to any material amount.

As will be seen, in each of the forms shown, the blow-imparting element or structure is a part of the stopple and does not affect the ability to position the stopple within or remove it from the apparatus. Hence the principles of the invention can be made applicable to any standard form of apparatus of this general class with a minimum expense, simply by substituting a stopple of the type herein indicated—varied to meet the general cross-sectional configuration of the particular type of such standard apparatus—for the standard stopple, this substitution being made without affecting any of the remaining elements of the apparatus.

As will be seen, a fundamental feature of the invention is the employment of a blow-imparting element freely movable relative to a gravity-stoppable and to impart a hammer-blow effect exerted in the direction of opening movement of the stopple, to provide such stopple opening movement in cases where gravity is insufficient to properly unseat the stopple. While I prefer to provide this result by the use of means of the general types herein disclosed, the invention contemplates obtaining this general result in other ways.

While I have herein shown and described various ways in which the principles of the present invention may be employed, it will be readily understood that changes or modifications therein may be found desirable or necessary in meeting the various exigencies of use, and I desire to be understood as reserving the right to make any and all such further changes or modifications as may be found desirable or deemed essential, in so far as the same may fall within the spirit

and scope of the invention as expressed in the accompanying claims when broadly construed.

What I claim is:

- 5 1. In fire-extinguishing apparatus adapted to be rendered active by inversion of the apparatus, an outer container having a neck, an inner receptacle having an open top and also having means extending into said neck
- 10 to space said open top relative to the neck, a gravity stopple normally seated to close said open top and movable relative to said means, and a blow-imparting element freely movable within and in the direction of length of
- 15 said receptacle to provide a hammer-like blow effect to said stopple exerted in the direction of stopple-opening movement when the apparatus is inverted, whereby said element may aid in the stopple unseating movement.
- 20 2. In fire-extinguishing apparatus adapted to be rendered active by inversion of the apparatus, the combination with the open-top component-receiving receptacle and its gravity stopple, of means within the receptacle for imparting a hammer blow effect to said stopple when the apparatus is inverted, said means being freely movable in the direction of length of the receptacle and exerting its blow action in the direction of stopple opening movement.
- 25 3. In fire-extinguishing apparatus adapted to be rendered active by inversion of the apparatus, the combination with the open-top component-receiving receptacle and its gravity stopple, of means for imparting a hammer-blow effect to said stopple when the apparatus is inverted, said means being supported by the stopple and freely movable in
- 30 the direction of length of the receptacle and exerting its blow action in the direction of stopple opening movement.
- 35 4. In fire-extinguishing apparatus adapted to be rendered active by inversion of the

apparatus, the combination with the open-top component-receiving receptacle and its gravity stopple, of a blow-imparting element supported by the stopple and freely movable in the direction of length of the receptacle.

50 5. A gravity stopple for fire-extinguishing apparatus comprising a body portion having a seating face, and a freely-movable blow-imparting element supported by said body portion to cause the blow-imparting movements of said element to be exerted in a direction to shift the stopple from its seat.

55 6. A gravity stopple for fire-extinguishing apparatus comprising a body portion having a seating face, a supporting structure projecting from said body portion within said seating face, and a blow-imparting element mounted within and freely movable in the direction of length of said structure.

60 7. A gravity stopple for fire-extinguishing apparatus comprising a body portion having a seating face, a cup-shaped supporting structure projecting from said body portion within said seating face, and a blow-imparting element mounted within and freely movable in the direction of length of said structure.

65 8. A gravity stopple for fire-extinguishing apparatus comprising a body portion having a seating face, said body portion having a projecting boss within said face, a cup-shaped supporting structure carried by said boss, and a blow-imparting element mounted within and freely movable in the direction of length of said structure.

70 80 In testimony whereof I have hereunto set my hand in presence of two subscribing witnesses.

CHARLES H. MEIGS.
